UNITED STATES PATENT OFFICE.

CHARLES J. DUNBAR, OF KALAMAZOO, MICHIGAN, ASSIGNOR TO LEFEBURE CORPORATION, OF CEDAR RAPIDS, IOWA, A CORPORATION OF IOWA.

LOOSE-LEAF BINDER.

Application filed August 11, 1928. Serial No. 299,025.

This invention relates to binders, and more particularly those of the type employed for holding loose leaves in such books as county records and the like.

5 The object of the invention is to improve binders of this nature so as to materially strengthen them at the leaf-holding portions, facilitate the insertion and removal of the leaf-holding posts, and so construct the posts 10 that the removal of leaves is effected easily and with little liability of tearing them.

The invention is fully disclosed in the description and claims following, reference being had to the accompanying drawing, in 15 which:—

Fig. 1 is an end elevation of the improved binder as seen from the lower end. Fig. 2 is a rear elevation of the same with the top cover and back thrown back as indicated by 20 the dotted lines in Fig. 1. Fig. 3 is a fragmentary end view, illustrating an open book. Fig. 4 shows one of the posts and its holders in cross section, as seen endwise of the book. Fig. 5 is a similar view, but showing the upper end of the post in section and the lower 25 end permanently attached to the leaf-clamping bar. Fig. 6 is an end view of a post and a fragmentary view of its lock-bar. Fig. 7 is an end view of a post, its neck being in section.

As herein set forth the invention is shown applied to a binder of a familiar type for holding loose leaves 5, punched to receive the binder posts 7. These are made attachable 30 to leaf-clamping bars 8 hingedly connecting the top and bottom covers 9 and 10, respectively, and the back member 11. The clamp-bars are usually of tubular construction, and enclose an endwise sliding lock-bar 12 to engage the posts in some manner and so hold 35 the leaves in closely clamped position. Ordinarily the book is used as indicated in Fig. 3. When it is desired to shift one or more leaves the upper cover is thrown back, after 40 sliding the lock-bar, as indicated by the dotted outline in Fig. 1.

The invention herein set forth refers more particularly to the post and its fastening, and will now be described.

50 Cylindrical posts 7, with ends preferably rounded, at least at the upper ends, are notched or grooved at 7^a for engagement with the lock-bar 12. As herein shown, the bar is pierced with key-hole slots 12^a, and has a terminal finger-piece 12^b by which it is

shifted endwise. The narrow portion of each slot engages the neck 7^a of the post under the head, and thus locks the binder together. The larger portion of the slot, as well as the adjacent hole 8^a in the clamping bar must be large enough to readily admit the post, or any number of them in a series, when the book is closed to lock the leaves, as is done by simply throwing the top cover to the closing position by a single sweeping motion. 60 If the posts are made removable from both covers, as is often the case, this leaves the posts with little support, especially when the lock-bar is withdrawn, and the whole body of leaves may then shift endwise so that in 65 re-closing a detached cover the posts and cover holes do not come in register. In order therefore to better support the posts in an upright position, when of the type shown in Fig. 4, sockets 7^c are formed in their ends, 70 and in the clamp-bars in line with the sockets are set studs 8^c to engage therewith. The posts are thus held steadily in a true vertical position, and will be in correct register with the cover in closing. The stud and socket 75 connection serves also to greatly strengthen the binder against the twisting and racking strains to which it is subjected in daily use. The hurried throwing over of masses of leaves in heavy county records, for example, 80 as indicated by any of the masses in Fig. 3, brings a heavy strain on the posts and their connections, tending to wrench, distort and even break the book at the post connections. The stud and socket joint is therefore of 85 material benefit in this respect, whether applied at both ends, as in Fig. 4, or only one end, as shown in connection with the fixed post 7^d in Fig. 5.

To quickly detach a leaf from the binder 90 the simplest way is to catch the leaf at the top edge and strip it off the posts, as indicated in Fig. 1. If on this upper side of the post there is a notch the hole in the leaf is pretty sure to engage it, and is very apt to 95 be torn. To prevent this tearing of leaves that portion of the posts herein designated as the neck is maintained flush with the body and head, as shown in Figs. 2 and 7, thus presenting a smooth unbroken surface over 100 which the leaf may slip in shifting.

To facilitate the engagement of the lock-bar with the posts, the necks of the posts are tapered at one side at 7^e so as to readily enter the narrow portions of the key-hole slots. 110

Having thus described my invention, I claim:

1. In a loose-leaf binder, the combination with a clamping bar provided with studs, of 5 leaf-holding posts provided with central terminal sockets to engage said studs, and means adapted to lock the posts to the bar.
2. In a loose-leaf binder, the combination with a clamping bar provided with studs, of 10 round-ended leaf-holding posts provided with central terminal sockets to engage said studs, and means adapted to lock the posts to the bar.
3. In a loose-leaf binder, the combination 15 with a clamping-bar adapted to receive a leaf-holding post and a post-engaging lock bar cooperating therewith, of a leaf-holding post formed with a narrow neck to engage the lock-bar, said neck extending transversely 20 substantially the full diameter of the post and tapered adjacent to one side of the post to facilitate engagement with the lock-bar.
4. In a loose-leaf binder, the combination 25 with a clamping bar provided with studs, of leaf-holding posts provided with terminal

30 sockets to engage said studs, a key-hole slotted bar cooperating with said clamping bar to lock the posts thereto, said leaf-holding posts being notched laterally to engage the lock-bar slots, the neck between notches extending transversely substantially the full diameter of the post.

35 5. In a loose-leaf binder, the combination with leaf-holding posts provided with terminal sockets, of a clamping bar adapted to receive the ends of said posts, with studs secured within the clamping bar and fitting said post-sockets, and means for releasably locking the posts within the clamping bar and in engagement with its studs.

40 6. In a loose-leaf binder, the combination with leaf-holding posts, of a hollow clamping bar having openings at one side to receive said posts, means for releasably locking the posts to said clamping bar, and interfitting 45 means between the ends of the posts and the inner face of the opposite side of said clamping bar.

In testimony whereof I affix my signature.

CHARLES J. DUNBAR.
